FIG. 1

FIG. 2

FIG. 3

George E. Cole
Inventor

By *Geo. Kimmel*
Attorney

UNITED STATES PATENT OFFICE.

GEORGE E. COLE, OF TIFFIN, OHIO.

SPECTACLE-CASE HOLDER.

1,300,124.

Specification of Letters Patent.

Patented Apr. 8, 1919.

Application filed January 30, 1919. Serial No. 274,062.

To all whom it may concern:

Be it known that I, GEORGE E. COLE, a citizen of the United States, residing at Tiffin, in the county of Seneca and State of Ohio, have invented certain new and useful Improvements in Spectacle-Case Holders, of which the following is a specification.

The present invention has reference generally to improvements in that class of inventions known as buttons, buckles and clasps and more particularly relates to an improved spectacle case holder.

It is the principal aim and object of this invention to provide a device of the above mentioned character designed to be attached to a garment such as a vest preferably at or above the rear wall or back of a pocket therein for receiving a spectacle case or other object and retaining the same against accidental displacement.

More particularly the present invention contemplates the provision of a device of the above mentioned character embodying an attaching plate having other plates pivoted to the side edges thereof while acting in conjunction with the opposed movable plates is the improved member designed to normally retain the movable plates spread so as to act in a retaining capacity against the case which is receivable in the device but in turn is movable away from the case when the movable plates are engaged and pressed toward each other to permit a quick removal of the case from the device.

Among the other aims and objects of this invention may be recited the provision of a device of the above mentioned character wherein the parts are comparatively few, the construction simple, the cost of production low and the efficiency high.

Other objects, as well as the nature, characteristic features and scope of this invention will be readily apparent from the following description taken in connection with the accompanying drawings and pointed out in the claims, forming a part of this specification.

The invention is clearly illustrated in the accompanying drawings, in which:—

50 Figure 1 is a top plan view showing the device attached to a garment with a spectacle case received therein, the pocket of the garment being shown in dotted lines,

55 Fig. 2 is a rear elevation of the same, and Fig. 3 is a transverse sectional detail of

the device detached and with the case removed.

Similar characters of reference are employed in all of the above described views to indicate corresponding parts.

Referring now, more particularly, to the accompanying drawings there is illustrated the improved spectacle case holder designated generally by the numeral 1 and in which is adapted to be received a spectacle case generally designated 2, the device being designed for attachment to a garment such as a vest preferably at or above the rear wall or back of a pocket therein such as indicated in dotted lines.

In the present instance the improved holder may be said to consist of a relatively flat and narrow attaching plate 3 formed of any desired material and is positioned through the instrumentality of suitable fastening or attaching means such as a pin shank 4 which is connected as at 5 to the rear face of the plate and subsequent to engagement with the garment is engaged with a keeper 6 also carried by the rear face of the plate. Relatively short side plates 7 are now swingably connected to the respective end or side edges of the plate 3. In establishing this connection the inner ends of the side plates are formed with ears 8 which are arranged between the spaced hinges 9 on the plate 3 while these alining or registering ears 8 and 9 are engaged by pintles 10 for suitably connecting the plates together, as is apparent.

As intimated, an improved resilient retaining member has been employed in the present instance being in the form of a leaf spring 11, the terminal attaching portions 12 of which are bent inwardly so as to be arranged at an angle slightly less than 90 degrees to the main portion, said terminal attaching portions being secured as by suitable fasteners 13 to the outer side faces of the side plates 7 while the spring is tensioned so as to normally hold the side plates in slightly spreading relation or at an angle slightly greater than 90 degrees from the attaching plate 3, the arrangement being clearly indicated in Fig. 1. In addition to holding the side plates in this relationship, the medial portion of the spring bears against the adjacent face of the case 2 clamping the case to the attaching plate to prevent accidental displacement thereof. In

order to release the spectacle case from the holder, assuming that the device is attached to the rear wall of the pocket slightly beneath the upper edge of the front wall, the user merely places his thumb and finger on the outside of the pocket so as to engage the outer ends of the side plates 7, exerting a pressure thereon drawing the plates 7 toward each other or bending the spring there-by removing the spring from its clamping or engagement or relation with respect to the case so that the case in consequence may be easily removed. By repeating the action of drawing the side plates together the user can replace the case in the holder, sliding the case downwardly into the pocket and when released the spring will automatically move the side plates farther apart and will also engage the case so as to prevent dis-placement thereof. It is of course apparent that other objects of a similar shape to the spectacle case may be conveniently carried without loss. Likewise, the holder may be made in different sizes to suit the size of the article or object to be held and also the size of the pocket.

It is believed in view of the foregoing description that a further detailed description of the operation of the invention is entirely unnecessary. Likewise, it is believed that the advantages of the invention will be readily apparent.

Still further embodiments of the invention than those herein especially defined may be resorted to as conditions or preference may

dictate, as may be in keeping with the hereto appended claims.

Having thus fully described the invention, what is claimed as new and desired to be secured by Letters Patent, is:—

1. A device of the character described including an attachment plate, side plates pivoted to the ends thereof, a spring clamping member, and attaching terminals extending angularly from the clamping member and secured to the side plates and to insure of the normal holding of the side plates in slightly spreading relation. 40 45

2. A device of the character described including an attaching plate, attaching means mounted on the rear face of the plate, opposed side plates pivoted to the opposite ends of the attaching plate, and a clamping member in the form of a leaf spring having its terminals bent to lie at an angle less than 50 55 60 65 90 degrees to the main portion of the spring, means for securing the terminal portions of the spring to the outer side faces of the side plates so that the spring will normally act to hold the side plates at an angle slightly more than 90 degrees with respect to the attaching plate to consequently allow the main portion of the spring to exert a clamping action on an object adapted to be insertible between the spring and attaching plate.

In testimony whereof, I affix my signature hereto.

GEORGE E. COLE.
